Des. 241,667
Patented Sept. 28, 1976

241,667

COMBINED FLOWER POT AND OVERFLOW DISH THEREFOR

Marten Gottsgegen, 1212 Lake Shore Drive,
Chicago, Ill. 60610

Filed May 16, 1975, Ser. No. 578,882

Term of patent 14 years

Int. Cl. D11—2

U.S. Cl. D11—152

Fig. 1

Fig. 2

Fig. 3

Fig. 4

Fig. 5

Fig. 7

Fig. 6

Fig. 8

FIG. 1 is a perspective view of a combined flower pot and overflow dish therefor showing my new design;

FIG. 2 is an exploded perspective view of a flower pot and water overflow dish showing my new design;

FIG. 3 is a top plan view thereof;

FIG. 4 is a front elevational view thereof;

FIG. 5 is a section view thereof;

FIG. 6 is a bottom elevational view of the flower pot showing my new design;

FIG. 7 is a bottom elevational view of the water overflow dish showing my new design; and

FIG. 8 is a top plan view of the water overflow dish showing my new design.

I claim:

The ornamental design for a combined flower pot and overflow dish therefor, as shown and described.
